S. F. HANZEL

JOKER FOR A PLAYING CARD

Filed Dec. 10, 1923

Inventor

Stanley F. Hanzel

By Sprinkle & Smith

Atys.

UNITED STATES PATENT OFFICE.

STANLEY F. HANZEL, OF CHICAGO, ILLINOIS.

DESIGN FOR A JOKER FOR A PLAYING CARD.

Application filed December 10, 1923. Serial No. 7,985. Term of patent 14 years.

To all whom it may concern:

Be it known that I, STANLEY F. HANZEL, a citizen of the United States, residing at Chicago, in the county of Cook and State of Illinois, have invented a new, original, and ornamental Design for a Joker for Playing Cards, of which the following is a specification, reference being had to the accompanying drawings, forming part thereof.

The figure is a plan view of a joker for playing cards, showing my new design.

I claim:

The ornamental design for a joker for a playing card, as shown.

STANLEY F. HANZEL.
